UNITED STATES PATENT OFFICE

ANDREW K. BARR, OF WAUKEGAN, ILLINOIS, ASSIGNOR TO WAUKEGAN FOUNDRY COMPANY, OF NORTH CHICAGO, ILLINOIS, A CORPORATION OF ILLINOIS

DESIGN FOR A COMBINED BASE AND STANDARD FOR STOOL

Application filed September 25, 1931. Serial No. 41,224. Term of patent 7 years.

To all whom it may concern:

Be it known that I, ANDREW K. BARR, a citizen of the United States, residing in the city of Waukegan, in the county of Lake and State of Illinois, have invented a new, original, and ornamental Design for a Combined Base and Standard for Stool, of which the following is the specification, reference being had to the accompanying drawings, forming part thereof.

Fig. 1 is an elevational view of the combined base and standard showing my new design;

Fig. 2 is a cross-sectional view taken along line 2—2 of Fig. 1; and

Fig. 3 is a cross-sectional view taken along line 3—3 of Fig. 1.

I claim:

The ornamental design for a combined base and standard for stool, as shown.

ANDREW K. BARR.
